ELECTRIC TOOTHBRUSH HANDLE

William H. Terrell, Akron, Ohio, assignor to Dominion
Electric Corporation, a corporation of Ohio

Filed Oct. 21, 1965, Ser. No. 87,697

Term of patent 14 years

(Cl. D9—2)

Fig. 1

Fig. 2

Fig. 4

Fig. 3

Fig. 5

FIGURE 1 is a top plan view of an electric toothbrush handle embodying my new design;

FIGURE 2 is a side view of the same, the other side being similar in appearance;

FIGURE 3 is a bottom plan view of the same;

FIGURE 4 is an end view of the same looking in the direction of the arrows 4-4 of FIGURE 1; and

FIGURE 5 is an end view of the same looking in the direction of the arrows 5-5 of FIGURE 1.

I claim:

The ornamental design for an electric toothbrush handle substantially, as shown and described.
